UNITED STATES PATENT OFFICE.

LOUIS W. GREVE, OF CLEVELAND, OHIO, ASSIGNOR, BY MESNE ASSIGNMENTS, TO THE CLEVELAND ROCK DRILL COMPANY, OF CLEVELAND, OHIO, A CORPORATION OF OHIO.

FLUID-OPERATED TOOL.

1,208,140.

Specification of Letters Patent. Patented Dec. 12, 1916.

Application filed March 12, 1914. Serial No. 824,263.

To all whom it may concern:

Be it known that I, LOUIS W. GREVE, a citizen of the United States, residing at Cleveland, in the county of Cuyahoga and 5 State of Ohio, have invented certain new and useful Improvements in Fluid-Operated Tools, of which the following is a specification.

The invention relates to fluid operated tools or machines, and particularly to fluid operated rock drills. The invention has for 10 its primary objects, the provision of an improved and simplified arrangement whereby fluid may be supplied through the drill steel when the operation of the hammer piston 15 has been stopped; the provision of means whereby the result above specified may be accomplished independently of the operation or position of the main valve (also referred to as the distributing valve or hammer piston controlling valve); the provision 20 of improved means for automatically locking the drill steel against movement in its chuck when the steel is being withdrawn 25 from the cavity drilled thereby, and the provision of improved means whereby the automatic locking means is brought into play with the stopping of the hammer piston and the cutting off of the air feed of the 30 drill. One embodiment of the invention is illustrated in the accompanying drawings, wherein—

Figure 1 is a longitudinal section through the machine, Fig. 2 is a partial plan view of the front end of the machine, Fig. 3 is a section on the line III—III of Fig. 2, Fig. 4 is an enlarged detailed section showing the steel clamping device, with the parts in a different position than that illustrated in 40 Fig. 1, Fig. 5 is a diagrammatic sectional view for showing the port arrangement, and Figs. 6 and 7 are diagrammatic sectional views showing the throttle valve in positions other than of Fig. 5.

Referring first to the general arrangement of parts as shown in Figs. 1 and 5; 1 is the main cylinder of the machine carrying the hammer piston 2, and anvil or tappet 3; 4 is the cylinder of the main or distributing valve 5; 6 is the throttle or admission valve for controlling the supply of fluid to the apparatus; 7 is the drill steel angular in cross section and slidably but non-rotatably fitting the chuck 8; 9 is the transversely working piston for securing the step-by-step

rotation of the chuck and drill steel carried thereby; 10 is the valve for controlling the movement of the piston 9, and 11 is a piston for feeding the machine ahead, such piston being carried by the feed cylinder 12.

The chuck 8 is operated by means of a ratchet wheel 13 engaged by a segmental member 14 toothed to fit the teeth of the ratchet wheel and having its upper end engaged by the piston 9, so that the oscillations of the piston rock the member 14 back and forth and cause a step-by-step rotation of the ratchet wheel 13 and the chuck 8 upon which it is mounted. This mechanism for securing the step-by-step rotation of the chuck and drill steel is shown, described, and claimed in my co-pending application Serial Number 784,359, filed August 12, 1913, and no detailed explanation nor claims with respect to this apparatus is therefore 75 made in the present application.

The hammer piston 2 is controlled from the valve 5 which reciprocates and alternately admits pressure to the opposite ends of the piston hammer to secure reciprocation. Substantially the same valve mechanism and arrangement of ports for securing the reciprocation of the hammer piston is disclosed in the patent to Richards No. 929,111 of July 25, 1909, and no claim is 85 made to this specific mechanism or arrangement of ports. In view of the fact that this mechanism is a part of the prior art and fully disclosed in the patent to Richards, only sufficient explanation of such 90 mechanism will be made in the present application as is necessary to an understanding of my invention and improvement to be later explained. The relation of the valve 5 and piston hammer 2 will be most readily 95 understood by a brief description of their operation. When the valve 5 and hammer piston are in the position indicated in Fig. 1, fluid pressure from the throttle valve 6 is admitted through the passage 15 leading through the hollow plug 16 and into the inclined passage 17. From the inclined passage 17 fluid passes into the groove 18 in the valve cylinder, thence to the groove 19, then back through the throttle valve via the passage 20 (refer now to Figs. 5 and 7), through the groove 21 in the throttle valve, to the passage 22, and thence to the front end of the cylinder. At this time pressure is being supplied to the chambers 23 and 24

at opposite ends of the valve 5, through the passages 25 and 26, the pressure in the chamber 23 being greater than in the chamber 24, by reason of the fact that the passage 25 is larger than the end of the passage 26 leading into the chamber 24, there being a constant discharge from each of the chambers through the small passages indicated at the upper sides of the chambers.

10 When the piston 2 moves to the rear it covers the end of the passage 25 and the groove 26. The covering of the end of the passage 25 cuts off the supply of pressure to the chamber 23 at the end of the valve 5 so that the pressure drops in this chamber, while the covering of the groove 26 causes an increase in the pressure in the chamber 24, such increase being due to the fact that the groove 26 is supplied with air from the 20 inclined passage 17, by means of the passage 27. The valve 5 is thus moved to the left. This movement to the left of course cuts off the supply of air through the passage 22 and permits a supply of air from the inclined passage 17 to pass to the left hand end of the hammer piston via the groove 28 and passage 29, so that pressure is applied to move the piston to the right. The movement of the piston to the left hand end 30 of the cylinder uncovers the end of the exhaust passage 30, such exhaust passage leading to the rear end of the machine and having its rear end open in the normal operation of the apparatus. The exhaust from the left hand end of the cylinder is accomplished by means of the branch passage 31 leading into the main exhaust passage 30.

The throttle valve 6 is of the tapered rotary type, and in the preferred construction 40 has three different positions of use, such positions being illustrated in Figs. 4, 5, 6, and 7. In order to make the construction clear, the showing in Figs. 5, 6, and 7, is diagrammatic, the various passages (with one exception) being placed all in the same plane, and in some cases being somewhat displaced from their actual positions in the machine, in order not to overlap and cause confusion. Referring now to 45 the passages in the throttle valve and controlled thereby, as illustrated in Figs. 5, 6, and 7, 32 is the passage through the valve through which fluid pressure is supplied; 33, 34, and 35 are passages communicating with the passage 32 and leading through the walls of the valve 6; 36 and 21 are grooves in the wall of the valve 6 which do not communicate with the passage 32; 38 is another passage lying in the wall of the valve 6, in a different plane from the passages 36 and 21, and adapted to connect the end of the 50 passage 39 leading to the feed cylinder 12 with the exhaust passage 40 when the valve is in the position of Fig. 5; 15, 20, 22, and 65 30 are passages heretofore referred to, the

passage 15 leading to the distributing valve, the passage 20 leading from the distributing valve to the throttle valve, the passage 22 leading from the throttle valve to the front end of the cylinder 1, and the passage 30 conducting the exhaust from the front end of the cylinder to the throttle valve; 41 is a passage leading from the throttle valve to the valve 10 which controls the means for rotating the drill steel, and 42 is an exhaust 75 passage leading from the throttle, such passage being connected to the exhaust passage 30 when the throttle valve is in one position.

When the throttle valve 6 is in the position indicated in Fig. 5, the passage 15 is 80 blanked, so that no fluid is supplied to the distributing valve or to the hammer piston, and such hammer piston is therefore stopped. At this time the front end of the cylinder is supplied with a continuous flow of fluid 85 by reason of the fact that the passage 35 is in communication with the passage 22. The fluid pressure supplied to the front end of the cylinder escapes through the passage 43 in the drill steel, at high pressure, thus insuring a thorough cleaning of the cavity 90 in which the drill is working. At this time a full head of pressure is maintained in the front end of the cylinder, for the reason that the exhaust passage 30 is blanked at its rear end by the throttle valve 6. At this time fluid pressure is supplied to the drill rotating means through the passage 41, such passage being connected with the passage 32 in the throttle valve by means of the passage 34. At this time, also the forward feed of the machine as secured by the feed piston 11 is stopped, the fluid behind the feed piston 11, Fig. 1, being exhausted through the passage 39 (Fig. 5) the end of which is connected with the passage 40 by means of the groove 38 in the wall of the valve 6. This position of the throttle valve in Fig. 5 is of course occupied during the cleaning operation, at which time it is desirable that the 100 drill steel should be rotated without actuation of the hammer piston, and that a large supply of air should be forced through the drill steel. It will be noted that when the parts are in the position of Fig. 5 the supply of air to the front end of the cylinder passes directly to such front end, without going to the distributing valve, so that the supplying of fluid through the drill steel at this time is entirely independent of the distributing 110 valve.

The position of the throttling valve as illustrated in Fig. 7 is what may be termed the working position of the valve, since this 115 position of the valve secures the actuation of the hammer piston. When the valve is in the position indicated in Fig. 7 air is supplied to the passage 15 through the seat 35, so that the hammer piston operates in the normal way, air being supplied to the left 120

hand side of the hammer piston via the passage 29 when the valve 5 is in its left hand position, and being supplied to the right hand or front side of the hammer piston via the passage 15, the grooves 18 and 19, the passage 20, the groove 21, and the passage 22, when the valve 5 is in its right hand position as illustrated in Fig. 5. It will be seen that when the valve is in the position of Fig. 7 a free exhaust can occur from the right hand side of the hammer piston 2, since the exhaust passage 30 is brought into communication with exhaust passage 42, the ends of the two passages registering with the groove 36. At this time the passage 41 which operates the drill rotating mechanism is supplied with fluid as is also the passage 39 which operates the piston 11 (Fig. 1) to feed the machine ahead.

When the throttle valve 6 is in the position of Fig. 6 all of the operating passages are blanked, with the exception of the passage 39 which leads to the feed cylinder 12, the throttle valve being moved to this position when it is desired to feed the machine ahead to its working position and before starting the hammer piston. By moving the valve 6 a slight distance farther counter clockwise the passage 39 is blanked.

Another feature of my invention relates to the provision of the fluid operated clamping means illustrated in Figs. 1 and 4 whereby the drill steel is clamped against removal from its chuck when the drill steel is being withdrawn from the work with the throttle valve 6 in the position indicated in Fig. 5. At this time the admission of fluid pressure continuously to the front end of the cylinder via the passage 22 serves to clamp the drill steel against movement through its chuck, in the manner hereinafter set forth.

As indicated in Figs. 4 and 1, the rear end of the chuck 8 is recessed at 45, and in this recess is fitted slidably a collar 46 provided on its upper side with a forwardly projecting leg 47 having a pin 47' for preventing the collar from moving too far to the left. In the wall of the chuck 8 opposite the end of the leg 7 is an inclined slot 48 in which is fitted the clamping ball 49 normally pressed to the left by means of the spring 50 lying in a recess in the wall of the chuck. When the hammer piston is operating and the drill and tappet 22 occupy the position indicated in Fig. 1, the spring 50 pushes the collar 46 to the left and causes the ball to move up in the inclined passage 48, so that it does not engage the drill steel. The drill steel is therefore perfectly free to slide through the chuck in the usual way when the impulse of the tappet is applied thereto. When, however, it is desired to withdraw the steel from the work, and the throttle is moved to the position indicated in Fig. 5,

a clamping action is secured by the ball 49. This is due to the fact that the fluid pressure applied continuously to the front side of the hammer piston through the passage 22 forces the tappet or anvil 3 and the drill steel forward from their normal position as illustrated in Fig. 1 to the position illustrated in Fig. 4, at which time the front end of the tappet 3 engages the collar 46, forcing it and the ball 49 to the right, so that such ball acts as a wedge between the inclined wall of the slot 48 and the drill steel, thus clamping the drill steel securely in position, so that it will not accidentally drop out when the machine is removed from the work. The foregoing of course constitutes only one of a number of different forms of clamping devices which might be operated automatically by fluid pressure upon the withdrawal of the steel from the work, all of which are contemplated by my invention.

What I claim is:

1. In combination in a fluid actuated machine having a cylinder and a hammer piston, automatic valve mechanism for controlling the operation of the hammer piston, a hollow drill steel with its passage in communication with the front end of said cylinder, and a throttle valve and connections whereby fluid pressure is supplied to the said valve mechanism and thence to the front end of the cylinder when the throttle valve is in one position and whereby the supply of fluid to said automatic valve is cut off and fluid pressure supplied direct from the throttle valve to the front end of the cylinder when such throttle valve is in another position.

2. In combination in a fluid actuated machine having a fluid operated distributing valve, a hammer piston controlled thereby, and a hollow drill steel, a throttle valve and connections whereby the movement of the throttle valve to one position secures a continuous supply of fluid through the drill steel and cuts off the supply of fluid to the distributing valve and whereby the movement of the valve to another position supplies fluid to the distributing valve and thence through the drill steel.

3. In combination in a fluid actuated machine having a distributing valve, a cylinder, a hammer piston therein, a drill steel having a passage communicating with the front end of the cylinder, and an exhaust passage leading from the front end of the cylinder, a throttle valve and connections whereby the movement of the throttle valve to one position secure a continuous supply of fluid to the front end of the cylinder and through the drill steel and cuts off the supply of fluid to the distributing valve and blanks the said exhaust passage.

4. In combination in a fluid actuated machine having a distributing valve, a cylin-

- der, a hammer piston therein, a drill steel having a passage communicating with the front end of the cylinder, and an exhaust passage leading from the front end of the cylinder, a throttle valve and connections whereby the movement of the throttle valve to one position secures a continuous supply of fluid to the front end of the cylinder and through the drill steel and cuts off the supply of fluid to the distributing valve and blanks the said exhaust passage and whereby the movement of the valve to another position opens the said exhaust passage, and supplies fluid to the distributing valve and thence through the drill steel.
5. The combination with a fluid actuated machine having a hammer cylinder, a hammer piston, a hollow drill steel with its passage communicating with the front end of the hammer cylinder and an automatic valve mechanism for controlling the operation of the hammer piston, of fluid supply controlling means whereby fluid pressure may be supplied continuously to the front end of the hammer cylinder and thence through the drill steel when the supply of fluid pressure to the valve mechanism is cut off.
6. The combination with a fluid actuated machine having a cylinder, a hammer piston, a hollow drill steel with its passage communicating with the front end of the cylinder, an exhaust passage from such front end and an automatic valve mechanism for controlling the operation of the hammer piston, of fluid pressure supply controlling means whereby the said exhaust passage may be closed and fluid pressure supplied continuously to the front end of the cylinder, and through the drill steel when the supply of fluid pressure to the valve mechanism is cut off.
7. In combination in a fluid actuated machine, a cylinder, a hammer piston, a drill steel, fluid actuated feed means for moving the machine forward, fluid actuated means for gripping the steel, and a throttle valve and connections whereby the said gripping means are actuated to grip the steel and hold it against longitudinal movement in the machine when the supply of fluid for operating the piston hammer and feed means is cut off.
8. In combination in a fluid actuated machine, a cylinder, a hammer piston, a drill steel and means operated by fluid pressure for clamping the steel securely against movement in the machine.
9. In combination in a fluid actuated machine, a cylinder, a hammer piston, a drill steel, means operated by fluid pressure for clamping the steel against outward movement, and a throttle valve and connections whereby fluid pressure is supplied to secure the clamping of the steel securely against movement when the hammer piston is stopped.

10. In combination in a fluid actuated machine, a cylinder, a hammer piston, a drill steel, means operated by fluid pressure for clamping the steel against outward movement, and means whereby fluid pressure is supplied to secure the clamping of the steel securely against movement when the hammer piston is stopped.

11. In combination in a fluid actuated machine, a cylinder, a hammer piston, a tappet, a drill steel, and a clamping means operated by the forward movement of the tappet for clamping the steel against forward movement with respect to the machine.

12. In combination in a fluid actuated machine, a cylinder, a hammer piston, a tappet, a drill steel, a clamping means operated by the forward movement of the tappet for clamping the steel against forward movement, and means whereby fluid pressure is supplied continuously behind the tappet when the hammer piston is stopped.

13. In combination in a fluid actuated machine, a cylinder, a hammer piston, a tappet, a drill steel, a clamping means operated by the forward movement of the tappet for clamping the steel against forward movement, and means whereby fluid pressure is supplied continuously behind the tappet and the exhaust from the front side of the hammer piston blanked when the hammer piston is stopped.

14. In combination in a fluid operated machine, a hammer cylinder, a hollow drill steel communicating with the front end thereof, a hammer piston, a fluid operated distributing valve, and means whereby fluid pressure may be supplied to the front end of the hammer cylinder and thence through the drill steel without passing to the distributing valve.

15. In combination in a fluid operated machine, a hollow drill steel, a hammer piston, a fluid operated distributing valve and fluid supply controlling means whereby fluid pressure may be supplied directly to the drill steel without passing to the distributing valve, the supply of fluid pressure to the hammer piston being cut off at such time or whereby the fluid pressure may be supplied to the drill steel via the distributing valve, the supply of fluid pressure for operating the piston being uninterrupted at such time.

16. In combination in a fluid operated machine, a cylinder, a hollow drill steel communicating with the front end thereof, a hammer piston, a throttle valve, a passage leading therefrom to the front end of the cylinder, a second passage leading from the throttle valve to the distributing valve, and connections controlled by the throttle whereby the supply of fluid may be conducted through the first passage to the front end of the cylinder, the second passage being blanked, or whereby the supply of fluid may

be conducted through the second passage to the distributing valve, then back to the throttle valve and then through the first passage to the front end of the cylinder.

5 17. In combination in a fluid actuated machine having a cylinder and a hammer piston, a drill steel, a motor for rotating the drill steel, a fluid supply inlet, and a throttle valve having a plurality of admission positions in all of which positions fluid is supplied to the motor for rotating the drill steel and to the cylinder.

10 18. In combination in a fluid actuated machine having a cylinder and a hammer piston, a drill steel, a motor for rotating the drill steel, a fluid supply inlet, and a throt-

tle valve having a plurality of admission positions in all of which positions fluid is supplied to the motor for rotating the drill steel and in one of which positions fluid is supplied to the cylinder to reciprocate the hammer piston and in another of which positions fluid is supplied to the cylinder without causing the reciprocation of the hammer piston.
